THERMIC SIPHON

Gust J. Christenson, Chicago, Ill., assignor to
Locomotive Firebox Company, Chicago, Ill., a
corporation of Delaware

Application July 8, 1935, Serial No. 30,288

5 Claims. (Cl. 122—68)

This invention relates to improvements in thermic siphons and it consists of the matters herein-after described and more particularly pointed out in the appended claims.

5 One of the objects of the present invention is to provide a thermic siphon for use in connection with a firebox of the combustion chamber type and which siphon is so formed as to have such flexibility as will prevent fractures developing from expansion and contraction caused by wide temperature changes.

A further object of the invention is to provide a multi-compartment siphon for use in a firebox of the combustion chamber type and wherein a part of one compartment is disposed in the combustion chamber and has an inlet neck that opens through one of the sheets thereof and the other compartment has an inlet neck that opens preferably through the front throat sheet, the last 20 mentioned neck though relatively straight, being of such length as to provide adequate flexibility.

Another object of the invention is to provide a multi-compartment thermic siphon including an inlet neck for each compartment, the longer neck being made integral with the body and communicating with the rear end thereof and at the same time being transversely staybolted so as to resist the high internal pressure generated therein.

30 The above mentioned objects of the invention as well as others, together with the many advantages thereof, will more fully appear as I proceed with my specification.

In the drawings:

35 Fig. 1 is a longitudinal vertical sectional view through a relatively short combustion chamber type of locomotive firebox embodying the preferred form of the invention.

Fig. 2 is a transverse vertical sectional view 40 through a part of the firebox as taken on the line 2—2 of Fig. 1.

Fig. 3 is a longitudinal vertical sectional view 45 through a relatively long combustion chamber type of locomotive firebox embodying a modified form of the invention.

Fig. 4 is a detail vertical sectional view on an enlarged scale, through one of the inlet necks for the siphon shown in Fig. 3, the plane of the section being indicated by the line 4—4 of Fig. 3.

50 Referring now in detail to that embodiment of the invention illustrated in Figs. 1 and 2 of the accompanying drawings, the firebox therein shown, which is of the comparatively shallow, combustion chamber type, includes the crown sheet 5 which merges into the inner side sheets

6, the inner back sheet 7 and inner throat sheet 8. The crown sheet extends forwardly of the inner throat sheet 8 to form the top of the combustion chamber 9. This chamber is closed at the front end by a flue sheet 10 and the bottom 5 11 of said chamber joins the front end of the inner throat sheet 8.

The outer back sheet is indicated at 12; the outer side sheets are indicated at 13 and the outer throat sheet is indicated at 14. Said sheets co-operate with the top sheet and outer side sheets 13 in forming the back water leg 15, the side water legs 16 and the front throat 17 respectively, all in communication with the water space 18 of the boiler. The back and side water legs and 15 the front throat are bottomed by a mud ring 19 and portions of the inner and outer back sheets are formed to coact in providing a fuel door opening 20.

In the firebox, is provided, one or more of the 20 improved siphons indicated, as a whole, as at 21. In certain sizes of fireboxes, where only one siphon is employed, the siphon is disposed in the vertical median plane of the firebox. Where two 25 of such siphons are employed as illustrated herein, such siphons are disposed, one on each side of said vertical median plane of the firebox.

Each siphon as herein shown comprises a flat hollow body formed to provide front and rear, relatively deep compartments or chambers 30 22—23 respectively, separated by an intermediate compartment 24 of less depth. The body includes laterally spaced side walls 25—25 and transversely rounded front and rear end walls 26 and 27 respectively. Said side and end walls are flared 35 outwardly around the entire top end of the body, by means of inside curved corners 28 to merge into a laterally extending flange 28a. This flange is fitted and welded as at 29 in a suitable longitudinal opening in the crown sheet. Thus the open top end of the siphon body provides a common discharge for all three compartments of the siphon body, into the water space of the boiler 40 above the crown sheet.

The front wall 26 of the body is disposed at a relatively steep angle extending downwardly and rearwardly from the crown sheet and provides but a relatively small amount of overhang for this end of the body. The rear wall 27 of the body is also disposed at a relatively steep angle, substantially opposite that of the front wall and extends downwardly and forwardly to merge into a rounded corner or nose 21a. That part of the 45 50 55

body defining the rear compartment 23 terminates in a stub-like tubular extension 31.

Associated with said rear compartment of the siphon body is a downwardly and forwardly 5 extending inlet neck 32 of substantial length. As shown herein, said neck is made from a piece of seamless tubing and the front end of said neck is anchored in a flexible diaphragm 33 preferably flanged up from the top portion of the inner front 10 throat sheet 8. The rear end of said neck is butt welded to the end of the body extension 31 above mentioned, as indicated at 34.

The bottom portion 35 of the front compartment 22 which is transversely rounded, is disposed above and arranged at a lesser inclination than that of the neck 32. This bottom portion along with the parts of the side and front end walls of the siphon body are formed to provide a stub-like tubular extension 36 for the front 15 compartment of the body. Said extension or neck receives one end of an inlet tube 37 which extends downwardly and is curved slightly outward to be secured in a suitable diaphragm-like opening in the bottom 11 of the combustion 20 chamber so as to open into the water space of the boiler at this point. The inlet tube 37 is also substantially the same as that of the neck 32. When two siphons are used in a firebox, the 25 inlet tubes for the front compartments of both siphons open through the bottom of the combustion chamber at points spaced, one on each side of the median line of said combustion chamber bottom.

30 The bottom of the intermediate compartment 24 is formed by the top portion or part of a substantially circular formation 38. Another portion of said formation merges into a rounded rear corner 39 for the front compartment and said 35 corner blends into the rounded bottom 35 of said compartment. A third portion of said substantially circular formation forms the front end for the rear compartment and merges into the top of the stub-like tubular extension 31.

40 Preferably the entire siphon body and the tubular extensions 31—36 therefor, are made from an integral sheet, cut to such shape that when folded upon itself by means of a suitable 45 form block, produces the body and extensions shown. Such an integral structure will have a line of weld extending the length of the front wall, along the bottom of the front compartment, around the substantially circular formation 38 50 and down along the top of extension 31. Also, a line of welding will follow down along the rear wall 27 to merge into the corner 27a, said line of welding being necessitated because of the removal of certain excess metal from the sheet, 55 that permits the making of the inclined rear wall of the body without a puckering or buckling at said corner. To brace the body of the siphon against internal pressures, the same is transversely staybolted as at 40. Due to the outline shape 60 of the body, less staybolts are required than in a conventional siphon body and this without 65 sacrificing the safety factor.

Instead of making the entire body and the main inlet neck from a single sheet of metal, 70 that part of the body comprising the front compartment may be made from a single sheet of metal and that part of the body comprising the rear compartment and the main inlet neck extension may be made from a single sheet of metal 75 and the two parts joined by butt welding at about

the middle of the intermediate compartment 24.

While a two part body requires more welding operations, it has certain advantages in the economy in plate material, due to the use of smaller sheets and to the manner in which the 5 grain of the metal in the two sheets thus used, may be disposed. Whichever way the siphon is fabricated, that is, either from one or two sheets of metal, the operation of the siphon is the same and the advantages gained over the conventional 10 siphons are likewise the same.

In either instance, the arrangement of the parts is such that the relatively long neck is under compression when in a cold condition as when 15 there is no fire in the firebox. Such compression, of course, is in relation to the body of the siphon and substantially equals the amount of the movement due to expansion, as when the firebox is being fired under service conditions. Under 20 such conditions, when the siphon is under service heat and pressure, only slight stresses, incapable of starting fracture at the inside corners 25 previously mentioned are present because the force of the expansion will return the neck and the upper part of the siphon to their normal positions and thus neutralize the movement thereof.

In Fig. 3 of the drawings, I have illustrated the invention as embodied in a firebox longer than that shown in Fig. 1 and having a combustion 30 chamber 9a of greater length. To adapt the siphon to the increased length of firebox and combustion chamber, the length of the siphon body 21a is increased accordingly. Preferably, this increase in length of the siphon body is made 35 up in the front end chamber 22a so that a goodly portion of said front end chamber is disposed entirely within said combustion chamber. With such a front end structure, the front wall 26a is arranged at a greater inclination than in 40 the structure shown in Fig. 1.

While the length of the front compartment is thus increased, the length of the rear compartment 23a preferably remains the same as before and its position or spacing with respect to 45 the inside back sheet 7a remains the same as before. Thus the distance between the tubular extension 31a and the inside throat sheet 8a becomes greater to necessitate an inlet 32a of 50 greater length.

By reason of the use of an inlet neck of greater length, greater flexibility in the neck is inherent. Therefore, in such a construction it may be preferable to staybolt the intake neck. Furthermore, 55 if the neck is stay bolted it is not necessary that it be of seamless tubing. The conventional practice of making the neck integral with the body may be followed when the device is so formed. Under such conditions the body of the siphon 60 may be made from one or more metal sheets of the proper outline shape folded to form the body and the neck 32a. The neck 32a will then be of a circular cross section having a line of butt welding 32b along its top as best shown in Fig. 4. Such a welded neck is preferably staybolted 65 as at 32c to reinforce the same against internal pressures. Under ordinary practice, a staybolted neck may have more rigidity, but due to the length of the neck herein described, the requisite 70 flexibility desired is still present. In all other respects, the siphon includes the same structure as that described in connection with Figs. 1 and 2.

When the use of an arch is desired in the fire- 75

box, arch tubes 41 may be employed in connection with the necks 32 or 32a and which arch tubes are arranged parallel with and in the inclined planes of said necks. Such an arch may consist of bricks 42 all of the same pattern shape at their side edges. This avoids the expense of using bricks of different pattern shapes at said edges. The bricks thus used will have a better supporting engagement upon the necks and arch tubes than is afforded by the bulge on the conventional siphon.

By reason of the construction described, it is apparent that because of the siphon having a greater length, the same increases the superficial area and consequently the heating surface of the siphon. This induces a greater water evaporating and steaming action and fore and aft water circulating action in the boiler so that quiescent areas are substantially eliminated and sediment accumulation prevented. Again, such a structure avoids the necessity of using a separate siphon in the combustion chamber and this of course, reduces manufacturing and installation costs.

25 While in describing the invention, I have referred in detail to the form, arrangement and construction of the various parts thereof, the same is to be considered only in the illustrative sense so that I do not wish to be limited thereto except as may be specifically set forth in the appended claims.

I claim as my invention:

1. In a locomotive boiler firebox having a combustion chamber, a hollow water steaming and circulating wall including a body, a tubular inlet neck for said wall communicating at one end with the front bottom part of the body and opening at the other end through a part of the combustion chamber into the adjacent water space of the boiler, a second tubular inlet neck communicating at one end with the rear bottom part of the body and opening at the other end into water space of the boiler rearwardly of the combustion chamber, said body having a single outlet opening through the crown sheet of the firebox for the discharge of water supplied to the body by said inlet necks.

2. In a locomotive boiler firebox having a combustion chamber, a hollow water steaming and circulating wall, the top of which presents an elongated opening in the crown sheet of the firebox with the front end of the said wall projecting into the combustion chamber, an inlet neck for the said front end of said wall and opening through a firebox sheet forming a part of the combustion chamber and a second inlet neck for the rear end of said water wall opening through a firebox sheet at a point rearwardly of the combustion chamber.

3. In a locomotive boiler firebox having a combustion chamber, a hollow water steaming and circulating wall, the top of which presents an elongated opening in the crown sheet of the firebox with the front end of the said wall projecting into the combustion chamber, an inlet neck for the said front end of said wall and opening through a firebox sheet forming a part of the combustion chamber, and a second inlet neck for the rear end of said water wall opening through a firebox sheet at a point to the rear of the combustion chamber, the second mentioned inlet being straight and having a length greater than the first mentioned one which is curved.

4. In a locomotive boiler firebox, a hollow water steaming and circulating wall including a body presenting an elongated opening in the crown sheet of the firebox and comprising spaced, staybolted sides butt welded at their meeting edges, each side including an integral semi-circular neck extension, butt welded at their meeting edges to form an inlet neck for said body communicating at one end with the water space of the boiler below the bottom of the flues therein and communicating at the other end with the bottom of the body at a point rearward of its front end, said neck being transversely staybolted.

5. A thermic siphon including a flat hollow body, a relatively long straight, downwardly extending inlet neck for the rear end of said body and a relatively short curved, downwardly extending inlet neck for the front end of the body.

GUST J. CHRISTENSON.
